TAUT WASHER FOR CLOTH

Henry A. Dameron, Greenville, S. C., assignor to
 Greenville Steel and Foundry Company, Greenville, S. C., a corporation of South Carolina

Application November 17, 1947, Serial No. 786,522

5 Claims. (Cl. 68—176)

1

This invention relates to a tight washer for cloth and is preferably used at the discharge end of a bleaching apparatus wherein the cloth is bleached and then it is passed through the present machine for washing the same.

It is an object of this invention to provide a tight washer for cloth in rope form in which the cloth is passed in spiral form over a plurality of top and bottom reels or rolls and through a bath of water for a plurality of times to remove the bleaching material therefrom and to discharge the cloth to other apparatus for future operations such as drying and folding or to dyeing machines and the like.

Some of the objects of the invention having been stated, other objects will appear as the description proceeds when taken in connection with the accompanying drawings, in which

Figure 1 is an isometric view looking at the rear portion of the apparatus;

Figure 2 is an end view looking at the left-hand end of the machine as shown in Figure 1 and showing the main drive shaft in section;

Figure 3 is a rear elevation of the machine;

Figure 4 is a vertical sectional view taken along the line 4—4 in Figure 3;

Figure 5 is a vertical sectional view taken along the line 5—5 in Figure 2;

Figure 6 is a sectional plan view taken along the line 6—6 in Figure 2 and showing portions broken away;

Figure 7 is a sectional plan view taken along the line 7—7 in Figure 3;

Figure 8 is a vertical sectional view taken along the line 8—8 in Figure 7;

Figure 9 is a vertical sectional view taken along the line 9—9 in Figure 8;

Figure 10 is an isometric showing of the interior portions of the machine such as the rollers and guide rail and the like;

Figure 11 is a vertical sectional view taken along the line 11—11 in Figure 5.

Referring more specifically to the drawings, the numerals 10 and 11 indicate channel base members which rest upon the floor, and at each corner thereof are secured by any suitable means such as screws 12, angle members 13 which have suitable holes 14 therein by means of which the channel base members 10 and 11 may be anchored to a suitable base disposed below the floor level. The floor level of the plant in which this machine is disposed is indicated by the line 15.

Rising upwardly and secured at their lower ends to the base channel bar 10 are upright frame members 16 and 17, and rising upwardly

2

from the base channel bar 11 are upright channel bars 18 and 19. Welded to the top ends of the upright channel bars 16 and 17 is a horizontal channel bar 22 and a similar bar 23 is disposed between and secured to the upper ends of the upright channel bars 18 and 19.

Secured between the proximate sides of the base channel bars 10 and 11 and bridging the gap therebetween are channel bars 25 and 26, and it will be noted that the channel bar 26 is at a higher elevation with respect to the horizontal than the channel bar 25, for purposes to be later explained. These channel bars 25 and 26 have secured therebetween suitable channel bars 27, 28 and 29. It will be noted that the base channel bars 10 and 11 extend substantially beyond the upright channel bars 16, 17, 18 and 19 respectively and suitable brace members 30 are secured between the outside surfaces of the upright channel bars above named and the ends of the base channel bars 10 and 11 for purposes of rigidifying the frame.

Secured between the proximate edges of the upright channel bars 16 and 17 is a channel bar 33, and above the channel bar 33 there is also disposed between the proximate surfaces of the upright channel bars 17 and 18 suitable channel bars 34 and 35. Suitable angle bars 36 and 37 are secured between the proximate surfaces of the upright channel bars 16 and 17 and the lower surface of the top channel bar 22. Secured to the horizontal upper channel bar 22 is a bearing mount 38 on which a bearing 39 is mounted.

Secured between the upright channel bars 18 and 19 is a channel bar 42 and also above this in spaced relation are secured the channel bars 43 and 44 and secured between the proximate surfaces of the upright channel bars 18 and 19, and the lower surface of upper channel bar 23, are angle bars 45 and 46. On the upper channel bar 23 is mounted a bearing mount 47 on which is mounted a bearing 48. Secured between the uprights 16 and 18 is a channel bar 50 and secured between the uprights 17 and 19 is a channel bar 51.

Resting on the transverse channel bars 25 and 26 and on the cross channel bars 27, 28 and 29 is a bottom portion 53 of a tub, broadly designated by reference character T. This bottom 53 slants toward the front side of the casing and has drain plugs 60 in each compartment. The front wall of this tub is indicated by the reference character 54, while the rear wall is indicated at 55. The rear wall is of less height than the front wall and is turned rearwardly and then

downwardly as at 56. The front wall 54 extends upwardly slightly above the horizontal channel bars 22 and 23 and is bent forwardly and downwardly as at 57. The two end portions of the tub T are indicated at 58 and 59. A pair of cover sections 63 and 64 are flanged as at 65 and 66 and are secured together by a plurality of bolts or rivets 67.

To the front lower edge of cover portion 63 is secured an angle bar 68 and the horizontal portion of angle bar 68 is secured to the upper end or flanged portion 57 of the front wall 54 by means of a plurality of bolts or rivets 70. The rear half of the cover 64 has secured to its rear lower edge an angle bar 71, whose horizontal leg is secured by any suitable means such as rivets or bolts 72 to a channeled portion 73 of a baffle plate 74 which extends inwardly and is curled at its free end as at 75.

It is thus seen that there is provided an opening 77 between the flanged portion 56 of the rear wall 55 and the baffle plate flange 73 through which access may be gained to the interior for threading the cloth around the reels or for repair work or for any other reason. Secured between the flanged portion 56 and the flanged portion 73 of baffle plate 74 is an upright angle bar 78, which has a plate 80 secured to its interior surface and said plate 80 is also secured to another angle bar 81 shown in Figure 6. Extending from the inside of the plate 80 are the brackets 83 and 84 in which is mounted an idler roller 85 underneath which the cloth passes in its exit from the machine.

The plate 80 has an opening 86 therein which is covered by means of a flanged portion 87 of a tube 88 being welded thereto. The cloth in leaving the machine passes through the tube 88. This tube 88 in Figure 1 is omitted for sake of clearness.

The cover section 84 has secured thereto handles 90 and 91 and the cover section 63 has secured thereto handles 92 and 93 by means of which the cover section can be removed from the main tub portion, when desired, by removing the bolts or rivets 70 and 72.

The front wall 54 has an entrance opening 95 therein through which the cloth enters into the machine. This opening is covered by a pot-eye 96 and on the inside surface of front wall 54 is mounted a pair of brackets 97 and 98 in which a roller 99 is mounted beneath which the cloth C passes as it enters the machine.

Immediately below the pot-eye 96 is disposed an opening 101 in which is mounted a funnel-shaped member 102 adapted to catch any drippings from the cloth C as it is constricted to enter the machine by the pot-eye 96, and thus any drippings from the cloth would be entered into the inside of the machine.

The end wall 58 has a suitable opening covered by a pipe 103 which is flanged at its outer end and receives a suitable flanged fitting 104, the two flanges being secured together by any suitable means such as bolts or rivets 105. A suitable inlet water pipe 106 is threadably secured in the member 104. On the inside of wall 58 is disposed a baffle 107 to deflect the water downwardly upon entrance into the machine, should it have sufficient velocity to be forced across a goodly portion of the interior of the machine.

The wall 59 has an overflow opening in the form of a pipe 110 welded therein which projects outwardly and is flanged at 111, and a suitable flanged member 112 is secured thereto by

any suitable means such as bolts or rivets 113 and a suitable drain pipe 114 is threadably secured in the flanged member 112.

Suitable water-tight translucent casings 116 and 117 are mounted on the interior of the walls 58 and 59 respectively, in which electric light bulbs 118 are mounted and suitable wires 120 and 121 lead from each one of these bulbs to a suitable source of electrical energy for illuminating the interior of the casing.

There is a suitable inspection opening 122 disposed in the front wall 54 through which the cloth may be viewed at any time during operation.

Secured to the bottom 53 and to the front and rear walls 54 and 55 by any suitable means such as welding are the baffles or partitions B-1 and B-2. The baffle B-1 has a portion 125 extending from the front wall to not quite half the distance to the rear wall, whose upper edge is flanged by being turned away from the end wall 58, and then it has a portion 126 which is parallel to the front and rear walls and then it has a portion 127 extending to the rear wall 55, the upper edge of which is flanged and the flange is projected toward the end wall 58. The baffle or partition B-2 has a portion 130 secured to the inner surface of the front wall 54, and it projects rearwardly the same distance as the portion 125 and is flanged at its upper end, which flange is directed toward the upper flange of portion 125. It then has a portion 131 extending toward the end wall 58, and then it has a portion 132 extending to and secured to the rear wall 55.

The top edges of baffles B-1 and B-2 are disposed in a horizontal place so the water spills evenly over all portions of them, but the top edge of baffle B-2 is about two inches lower than the top of baffle B-1.

Mounted on the interior surface of end walls 58 and 59 on the vertical portions 125 and 130 of the baffles B-1 and B-2 and also on the proximate faces of the baffle portions 127 and 132 are bearing box assemblies, a description of one of which will be given and like reference characters will apply to the others as they are all identical.

These bearing box assemblies comprise a plate member 135 having a plurality of holes 136 therethrough which are penetrated by bolts or rivets 137 to secure the plate to the respective portions above enumerated. Each of these plates 135 has a leg portion 138 and to the lower side of horizontal portion 138 and to the lower portion of the plate 135 is secured a plurality of angle clips 139 for supporting the horizontal portion 138. The horizontal portion 138 has mounted thereon a plate member 140 having elongated slots 141 therein through which bolts 142 may be passed and through the holes 143 in the horizontal portion 138 to secure the plate 140 in position. The plate 140 has integral with its upper surface an inverted U-shaped portion 144 which is reinforced by angle clips 145 and 146 on the sides thereof which are also secured to the upper surface of the plate 140.

Fitting snugly within the confines of the inverted U-shaped member 144 is an oil bearing block 150. There is a shim 151 disposed at the lower edge of this block 150 and resting on the plate 140, whereby when the bolts 142 are driven home, they will exert a binding effect on the bearing 150 to hold it in position. The slots 141 in each of the plate members 140 permit longitudinal adjustment of each bearing member 150 relative to the supporting horizontal portion 138.

Rotatably mounted in the above described

bearings 150 are the reels R-1, R-2 and R-3. Since the structure of each of these reels is identical, like reference characters will apply to the individual parts thereof. Each reel comprises a tubular member 155 having heads 156 and 157 secured thereon by any suitable means such as welding and these heads 156 and 157 are suitably perforated in a circle and a plurality of shafts 158 are mounted in these perforations by any suitable means such as welding, and disposed between the heads 156 and 157 and mounted on the tubular member 155 are spacer discs 160 and 161 which are welded to the tubular member 155 and have a plurality of semi-circular cavities in their peripheries into which the shafts 158 are adapted to fit.

The top roll, which is a driven roll is mounted near the top of the machine and extends from one end of the machine to the other and this roll comprises a cylindrical shell 165 having heads 166 and 167, welded or otherwise secured in the ends thereof, and secured centrally in these heads 166 and 167 are outwardly projecting stub shafts 168 and 169 which are mounted in the bearings 39 and 48 respectively. The cylindrical member 165 has a tubular resilient covering 170 such as rubber. The stub shaft 168 has a portion 171 of a coupling member and a companion registering coupling member 172 is secured on a motor shaft 173 extending from an electric motor 174 having wires 175 and 176 extending therefrom to any suitable source of electrical energy. The electric motor may be supported by any suitable means, one form of support being a table 177 disposed at the proper elevation to cause the couplings 171 and 172 to mesh with each other.

In order to properly guide the cloth C through the apparatus, suitable guiding mechanisms must be provided. It will be noted that to the inside surfaces of end walls 58 and 59 are secured plates 180 and these plates have projecting therefrom parallel spaced plates 181 and 182, which have suitable registering holes therein penetrated by bolts 183 which also penetrate suitable holes 184 in the ends of a bar 185. The bar 185 is rectangular in cross section and to the front side wall are secured two sets of pins 186 and 187, alternate pins being disposed at different elevations. On the rear side of the bar 185 and at the central portion thereof is mounted a plurality of pins 188 which are rearwardly projecting and which have upper and lower rolls with alternate pins staggered in an up and down relation, the purpose of which is to guide the cloth C in its travel through the washer.

Method of operation

A washer of this type is usually a rather large machine eight to ten feet high and four to five feet from front to rear and of any desired length and therefore it is easy for a workman to enter the machine through the opening 71. Before the machine is ready for operation, of course, an operator would enter the machine through opening 71 and the cloth C in rope form would be passed through entrance pot-eye 96 and beneath roller 99 and beneath the top roll R-4 which is the rubber covered roll. Then the cloth is led over the roll R-4 and downwardly to the front side of the first reel R-1 and beneath this reel R-1 and up through the first set of pins in the right-hand of Figure 10 and again over the roll R-4 and this operation is repeated for a plurality of times until convolutions of cloth appear between all of the pins 186. Then the cloth is

again passed over the top roll R-4 and beneath the second reel R-2 and then upwardly between the first set of pins 188 and this is continued until convolutions of the cloth appear between all of the pins 188. Then the cloth is passed finally over roll R-4 and downwardly on the front side of the third reel R-3 and beneath this reel and upwardly between the first set of pins 187 and convolutions of the cloth are continued until a convolution of cloth appears between each set of pins 187 and finally the cloth is passed over the roll R-4 and beneath the reel R-4 and then beneath the idler roller 85 and through the exit tube 88 to any suitable processing machine for processing the cloth after it has been thoroughly washed.

When the machine has been fully threaded, it being understood that the convolutions of cloth are tautly disposed around the reels R-1, R-2 and R-3 and the top roll R-4, then water is admitted to the interior of the machine through inlet pipe 106 which connects to inlet opening 103. The machine is filled with water up to the point where it overflows through the overflow opening 110 and a sufficient volume of water is passed through the machine to continuously renew the water therein. It will be noted that the water as it enters the machine drops into a first compartment or chamber C-1 in which the third reel R-3 is mounted and which is defined by the partition B-1 and the end wall 58. It will be noted that this partition B-1 has its top edge disposed in a horizontal plane and thus the water will spill over equally at all points along the partition B-1 and will fall into the second compartment or chamber C-2 in which the second reel R-2 is mounted and which is defined by the partitions B-1 and B-2. The partition B-2 is identical except being opposite hand to partition B-1 and its top edge is in a horizontal plane but slightly lower than the partition B-1 as is evident by referring to Figure 5. The water will fall over the top of partition B-2 into a third compartment or chamber C-3 in which the first reel R-1 is mounted and will circulate, of course, through this compartment C-3 and leave the machine through the exit or overflow opening 110. The machine is now ready for operation and electrical energy is then supplied to electric motor 174 which drives the roll R-4 and this in turn drives all of the reels R-1, R-2 and R-3 which are idler reels, but owing to the tension of the cloth, they are rotated by the travel of the cloth through the machine.

In the drawings and specification there has been set forth a preferred embodiment of the invention, and although specific terms are employed, they are used in a generic and descriptive sense only, and not for purposes of limitation, the scope of the invention being defined in the claims.

I claim:

1. In a taut washer for cloth, a casing having an entrance port and an exit port, a pair of spaced transverse partitions extending from the bottom of the casing upwardly and terminating at a point approximately one-third the height of the casing thus dividing the lower portion of the casing into a first, a second and a third chamber, said partitions extending from the wall on the entrance side of the casing to a point midway of the casing and then extending away from each other in a plane parallel to the entrance wall of the casing, and then extending to the wall on the exit side of the casing thus forming

the first and third chambers of L-shaped formation and a second chamber of T-shaped formation, a single idler reel mounted in each of the said chambers, the idler reels in the first and third chambers being in alignment with each other in the bottom of the casing, the axis of the idler reel in the second chamber being parallel to but in off-set relation to the axis of the reels in the first and third chambers, the idler reel in the second chamber having its ends extending past the proximate ends of the reels in the first and third chambers, a driven roller disposed near the top of the casing and extending for a distance equal to the combined length of the reels in the first and third chambers and being parallel to all of said reels, a cloth guide bar disposed intermediate the driven roller and the idler reels and in off-set relation thereto, a plurality of guiding spokes extending laterally from the guide bar, a water inlet port in one side of the casing and a water overflow port in the other side of the casing whereby a rope of cloth may be drawn into the casing through the entrance port by the driven roller beneath and over which the rope of cloth may pass and may be directed into the third chamber and around the idler reel therein and then outwardly over the driven roller spirally for a number of times and the cloth may be guided by the spokes in the guide bar as the rope of cloth passes from the driven roller to the idler reel in the third chamber and then the cloth may be guided by the said spokes to the reel in the second chamber a number of times in a spiral manner while still passing around the reel in the third chamber and then the cloth may be guided by the spokes from the driven roller around the reel in the first chamber a number of times in a spiral manner while still passing around the reel in the second chamber and then the cloth may be directed beneath the driven roll and outwardly through the exit port of the casing at the side remote from the entrance port for the cloth.

2. In a taut washer for cloth in rope form, a casing having a front wall and a rear wall and having side walls connecting the same, and a bottom member connected to the lower edges of the said walls, a driven roller mounted in the top portion of the side walls and spanning the distance therebetween, the front wall having an entrance port and the rear wall having a discharge port, a first reel rotatably mounted near the bottom of the casing and adjacent the front wall and having its axis disposed in parallel relation to the driven roller, a second reel rotatably mounted near the bottom of the casing and adjacent the rear wall of the casing and having its axis parallel to the driven roller, a third reel rotatably mounted near the bottom of the casing in alignment with the axis of the first reel, the proximate ends of the first and third reels being spaced from each other a distance less than the axial length of the second reel whereby the second reel has its ends extending past the ends of the first and third reels, a guide bar extending between the side walls and having a first set of spokes extending from the front side thereof and disposed above and rearwardly of the first reel, the guide bar having a second set of spokes extending from the rear side thereof and disposed above and forwardly of the second reel, said guide bar having a third set of spokes extending from the front side thereof and disposed above and rearwardly of the third reel, the cloth being adapted to be led through the entrance port beneath and over the driven roller to the side thereof adjacent the entrance port and then downwardly below the first reel and upwardly through the first set of spokes for a plurality of times to spirally guide the cloth, the cloth then being adapted to be led downwardly from the driven roller through the second set of spokes and then around the second reel and back around the driven roller for a plurality of times while

port beneath and over the driven roller to the side thereof adjacent the entrance port and then downwardly below the first reel and upwardly through the first set of spokes for a plurality of times to spirally guide the cloth, the cloth then being adapted to be led downwardly from the driven roller through the second set of spokes and then around the second reel and back around the driven roller for a plurality of times while still passing around the first reel, the cloth then being adapted to be led downwardly between the third set of spokes and below the first reel and upwardly around the driven roller for a plurality of times while still passing around the second reel and a guiding roller for guiding the cloth from the driven roller to the discharge port, the casing having first and second partitions rising from the bottom thereof and defining first, second and third compartments, the partitions having parallel portions in which the proximate ends of the first and third reels are mounted, the partitions also having diverging portions disposed in alignment with each other, and the partitions also having parallel portions disposed farther apart than the first parallel portions and in which the ends of the second reel are rotatably mounted, the partition between the first and second reels being of lesser height than the partition between the second and third reels, a supply pipe feeding into the first compartment and a discharge pipe leading from the third compartment.

3. In a taut washer for cloth in rope form, a casing having a front wall and a rear wall and having side walls connecting the same, and a bottom member connected to the lower edges of the said walls, a driven roller mounted in the top portion of the side walls and spanning the distance therebetween, the front wall having a cloth entrance port and the rear wall having a cloth discharge port, a first reel rotatably mounted near the bottom of the casing and adjacent the front wall and having its axis disposed in parallel relation to the driven roller, a second reel rotatably mounted near the bottom of the casing and adjacent the rear wall of the casing and having its axis parallel to the driven roller, a third reel rotatably mounted near the bottom of the casing in alignment with the axis of the first reel, the proximate ends of the first and third reels being spaced from each other a distance less than the axial length of the second reel, a guide bar extending between the side walls and having a first set of spokes extending from the front side thereof, the guide bar having a second set of spokes extending from the rear side thereof, said guide bar having a third set of spokes extending from the front side thereof, the cloth being adapted to be led through the entrance port beneath and over the driven roller to the side thereof adjacent the entrance port and then downwardly below the first reel and upwardly through the first set of spokes for a plurality of times to spirally guide the cloth, the cloth then being adapted to be led downwardly from the driven roller through the second set of spokes and then around the second reel and back around the driven roller for a plurality of times, the cloth then being adapted to be led downwardly between the third set of spokes and below the third reel and upwardly around the driven roller for a plurality of times and a guiding roller for guiding the cloth from the driven roller to the discharge port, a first partition secured to the bottom and front and rear walls of the casing, and separating the second and third reels, a sec-

ond partition secured to the bottom and the front and rear walls and separating the first and second reels and being of lesser height than the first partition and thus forming a compartment for the first reel, a compartment for the third reel and a compartment for the second reel, a water supply pipe communicating with the first compartment in which the third reel is mounted and a discharge pipe communicating with the compartment within which the first reel is mounted, whereby water will cascade over the first partition from the first compartment in which the third reel is mounted into the second compartment in which the second reel is mounted and then cascade into the third compartment in which the first reel is mounted.

4. In a taut washer for cloth in rope form, a casing having a front wall and a rear wall and having side walls connecting the same, and a bottom member connected to the lower edges of the said walls, a driven roller mounted in the top portion of the side walls and spanning the distance therebetween, the front wall having an entrance port and the rear wall having a discharge port, a first reel rotatably mounted near the bottom of the casing and adjacent the front wall and having its axis disposed in parallel relation to the driven roller, a second reel rotatably mounted near the bottom of the casing and adjacent the rear wall of the casing and having its axis parallel to the driven roller, a third reel rotatably mounted near the bottom of the casing and having its axis in alinement with the axis of the first reel, the proximate ends of the first and third reels being spaced from each other a distance less than the axial length of the second reel, a guide bar extending between the side walls and having a first set of spokes extending from the front side thereof, the guide bar having a second set of spokes extending from the rear side thereof, said guide bar having a third set of spokes extending from the front side thereof, the cloth being adapted to be led through the entrance port beneath and over the driven roller to the side thereof adjacent the entrance port and then downwardly below the first reel and upwardly through the first set of spokes for a plurality of times to spirally guide the cloth, the cloth then being adapted to be led downwardly from the driven roller through the second set of spokes and then around the second reel and back around the driven roller for a plurality of times, the cloth then being adapted to be led downwardly between the third set of spokes and below the third reel and upwardly around the driven roller for a plurality of times, a guiding roller for guiding the cloth from the driven roller to the discharge port, a first partition secured to the bottom and front and rear walls of the casing, and separating the second and third reels, a second partition secured to the bottom and the front and rear walls and separating the first and second reels and being of lesser height than the first partition and thus forming a third compartment for the first reel, a second compartment for the second reel and a first compartment for the third reel, a water supply pipe communicating with the first compartment and a discharge pipe communicating with the third compartment, whereby water will cascade over the partition from the first compartment in which the third reel is mounted into the second compartment in which the second reel is mounted and then cascade into the third compartment in which the first reel is mounted, all of said reels being mounted for rotation in vertically disposed guideways to cause their weight to exert pressure on the cloth, a pair of partitions forming separate compartments for the three reels, a water supply pipe connected to the compartment in which the third reel is mounted, a discharge pipe connected to the compartment in which the first reel is mounted, the partition adjacent the discharge compartment being of lesser height than the partition adjacent the intake compartment.

5. In a taut washer for cloth in rope form, a casing having a front wall and a rear wall and having side walls connecting the same, and a bottom member connected to the lower edges of the said walls, a driven roller mounted in the

top portion of the side walls and spanning the distance therebetween, the front wall having an entrance port and the rear wall having a discharge port, a first reel rotatably mounted near the bottom of the casing and adjacent the front wall and having its axis disposed in parallel relation to the driven roller, a second reel rotatably mounted near the bottom of the casing and adjacent the rear wall of the casing and having its axis parallel to the driven roller, a third reel rotatably mounted near the bottom of the casing and having its axis in alinement with the axis of the first reel, the proximate ends of the first and third reels being spaced from each other a distance less than the axial length of the second reel, a guide bar extending between the side walls and having a first set of spokes extending from the front side thereof, the guide bar having a second set of spokes extending from the rear side thereof, said guide bar having a third set of spokes extending from the front side thereof, the cloth being adapted to be led through the entrance port beneath and over the driven roller to the side thereof adjacent the entrance port and then downwardly below the first reel and upwardly through the first set of spokes for a plurality of times to spirally guide the cloth, the cloth then being adapted to be led downwardly from the driven roller through the second set of spokes and then around the second reel and back around the driven roller for a plurality of times, the cloth then being adapted to be led downwardly between the third set of spokes and below the third reel and upwardly around the driven roller for a plurality of times, a guiding roller for guiding the cloth from the driven roller to the discharge port, a first partition secured to the bottom and front and rear walls of the casing, and separating the second and third reels, a second partition secured to the bottom and the front and rear walls and separating the first and second reels and being of lesser height than the first partition and thus forming a third compartment for the first reel, a second compartment for the second reel and a first compartment for the third reel, a water supply pipe communicating with the first compartment and a discharge pipe communicating with the third compartment, whereby water will cascade over the partition from the first compartment in which the third reel is mounted into the second compartment in which the second reel is mounted and then cascade into the third compartment in which the first reel is mounted, all of said reels being mounted for rotation in vertically disposed guideways to cause their weight to exert pressure on the cloth.

HENRY A. DAMERON.
